SUBAQUEOUS DRIVING APPARATUS

Filed Oct. 13, 1927

UNITED STATES PATENT OFFICE

GEORGE F. WILSON, OF AKRON, OHIO, ASSIGNOR, BY MESNE ASSIGNMENTS, TO
AMERICAN ANODE INC., OF AKRON, OHIO, A CORPORATION OF DELAWARE

SUBAQUEOUS DRIVING APPARATUS

Application filed October 18, 1927. Serial No. 225,977.

This invention relates to sub-aqueous driving apparatus, and more particularly to apparatus for imparting rotary motion to an article which is partly or totally immersed in a liquid bath.

The invention is useful in plating or coating processes wherein it is desirable to rotate the article to be plated or coated to assure a uniform deposit thereupon, but exercises its 10 primary advantages when used in coating processes involving the use of colloidal dispersions such as natural or artificial aqueous dispersions of rubber, with or without added ingredients, wherein the dispersed particles 15 readily flocculate or agglomerate under certain conditions, as when the dispersion is in contact with frictionally sliding surfaces.

It is an object of this invention to provide driving means for submerged articles which 20 means do not pass through the walls of the receptacle in which the article is submerged. Another object is to provide driving apparatus of such mobility as to permit it readily to be immersed in and removed from a liquid bath. Another object is to provide driving 25 means of the character described wherein liquid is excluded from the operative parts of the apparatus. Other objects will be manifest from the detailed description of 30 the apparatus.

The accompanying drawing is illustrative of apparatus embodying my invention in its preferred form, parts being sectioned and broken away. Fig. 1 represents the apparatus 35 as a whole, while Fig. 2 is a detailed view on a larger scale of the portion of the apparatus which directly supports the work.

Referring to the drawing, 10 is a processing receptacle containing a liquid bath 11, and 40 12 is a tubular article or mandrel upon which a deposit from the bath 11 is made, such a deposit being shown thereon at 13. The mandrel is supported in horizontal position by mechanisms which engage its respective end portions, one of said mechanisms 45 including driving means for rotating the mandrel upon its own axis, the entire supporting and driving structure being adapted to be raised and lowered at will, upon occasion, such as the removal therefrom of a

coated mandrel and the mounting therein of another mandrel to be coated.

The mandrel supporting and driving mechanisms are suspended from a frame 14 which comprises a pair of laterally-spaced, 55 parallel, horizontal bars 15, 15 having their end portions secured in respective brackets 16, 16, the latter being slidably mounted upon vertical guides, such as the guide 17, positioned at opposite ends of the receptacle 10. 60 The frame 14 is thus positioned over said receptacle and adapted to be manually raised and lowered, a depending counter-weight 18 being provided for holding the frame at the desired elevation by means of cables 19, 19, 65 which pass over sheaves, such as the sheave 20, in the upper portion of the respective guides 17 and connect said counterweight with the frame-brackets 16.

Mounted upon the horizontal bars 15 adjacent one end thereof is an adjustable journal bracket 21 which includes a fixed vertical sleeve 22, the upper end of the latter supporting a thrust bearing 23 and the lower end thereof supporting a generally arcuate bearing structure 24 comprising a tubular portion 24a which is secured in said sleeve, a medial, arcuate, split portion 24b extending downwardly therefrom, and an integral tubular portion 24c at the free end of said split 70 portion, the axes of the tubular portions 24a and 24c being at right angles to each other. In the tubular portion 24a is a bearing bushing 25, and the arcuate portion 24b is recessed at 26, 26 to provide spaces for 75 meshing gears, the intermediate portions between said recesses being formed as bearing faces for the shafts of said gears. The arcuate split portion 24b is provided with a complementary cover which is secured thereto 80 by bolts 27, 27.

Mounted in the bearings 23, 25 is a vertical shaft 28 having its lower end provided with a bevel gear 29 and its upper end provided with a worm-wheel 30 which is meshed with a worm-gear 31 journaled upon a bracket 32 secured to the sleeve 22. The worm-gear 31 is driven from any suitable source of power, its shaft 32 preferably being provided with a universal joint 33 connecting with a drive- 95 100

shaft 34 having therein a slip-joint 35 and connecting, through a universal joint 36, with the source of power. Thus, the shaft 28 may be constantly driven at whatever elevation the frame 14 is positioned.

The bevel gear 29 is meshed with a bevel gear 37 mounted upon one end of an obliquely disposed shaft 38 which is journaled in the split portion 24b of the bearing structure 24, the other end of said shaft having mounted thereon a bevel gear 39 which is meshed with a bevel gear 40 mounted upon the adjacent end of a horizontal shaft 41 which is journaled in the tubular portion 24c of the bearing structure 24.

A thrust washer 42 is mounted upon the outer end portion of the shaft 41 abutting the bearing structure 24, as shown in Fig. 2, and a shouldered bushing 43 also is mounted upon said shaft 41 abutting the washer 42. Secured upon said bushing is a forwardly tapered collar 44 having a rearwardly extending circumferential flange or apron 45 which overlies the tubular portion 24c of the bearing structure 24, said collar 44 and its flange 45 constituting a seat for a bell-shaped rubber cap 46, the latter having a portion which extends over the forward end of the tapered collar 44 and bushing 43 and being clamped thereagainst by a cylindrical block 47 which is threaded onto the end of the shaft 41. The block 47 is provided with four radial slots 61 in which are disposed contact fingers 48 pivoted on pins 62. The fingers 48 are yieldingly pressed against the interior of the mandrel 12 by means of coil springs 63, whereby electrical contact is established between the mandrel 12 and the bearing structure 24, through the intermediary of the block 47 and the horizontal shaft 41. The tapered portion of the cap-covered collar 44 is adapted to enter one of the open ends of the tubular mandrel 12, and the bell-shaped portion of the cap 46 is so shaped as to overlie and snugly embrace the end portion of said mandrel for a short distance, and terminates in an outwardly flared portion 49 adapted to facilitate insertion of the mandrel into the cap and to effect a beveled or skived end on the deposit 13 on said mandrel. The frictional engagement of the cap 46 with the mandrel 12 is sufficient to rotate the latter when the cap is rotated through the shaft 41 and associated gears and shafts from the drive-shaft 34.

To protect the bearing structure 24 in Fig. 1 from the fluid 11 and to obviate the use of packing and stuffing boxes therein; the entire structure is covered with a flexible rubber sleeve 50 which has cylindrical end portions and a helically corrugated medial portion, the latter being internally reinforced with a coiled spring 51. The lower end portion of the sleeve 50 fits tightly over that portion 65 of the cap 46 which rests upon the flange

45 of the collar 44, and the other end portion of the sleeve loosely embraces the lower end of the bearing sleeve 22, which is above the liquid level of the bath 11, the intermediate, corrugated portion of the sleeve fitting loosely around the arcuate portion 24b of the bearing structure 24. The sleeve 50 is thus adapted to exclude liquid from contact with the bearing structure 24 and metal parts associated therewith, and is free to rotate upon its own arcuate axis when the mandrel-engaging cap 46 is rotated during the operation of the apparatus. The sleeve 50 also prevents solids from the bath 11 from being deposited upon the mandrel-supporting structure, and prevents contamination of the liquid bath which would occur where the constituents of the bath have a corrosive effect upon metal.

For supporting the other end of the mandrel 12, a bracket 52 is pivotally mounted at 53 between the horizontal bars 15 at their opposite ends from the journal bracket 21, said bracket being provided with an upstanding arm 54 which is connected by a pull-spring 55 with the adjacent bar-supporting bracket 16, so as normally to urge the bracket 52 downward around its pivot 53. Depending from the bracket 52 is a bearing structure 24, cap 46, and sleeve 50 together with associated parts identical with those at the other end of the frame 14 except that gears and shafts are omitted from the bearing structure 24. The arrangement is such that the cap 46 yieldingly engages the mandrel-end to support the same, under the urge of the spring 55, and said cap is free to rotate with the mandrel as the latter is rotatably driven from its opposite end.

A pipe 56 is suspended from the parallel bars 15 directly over the mandrel 12, being secured to said bars by straps 57, 57, and having one end closed and its other end connected to a flexible pipe 58 leading to a source of supply of air under pressure. Mounted in the pipe 56 is a manually operable valve 59, and a plurality of spaced-apart, downwardly extending, angular nozzles 60, 60 which are adapted to direct jets of air, at an angle, against the uppermost face of the mandrel throughout the entire length thereof.

In the operation of the apparatus, the frame 14 and associated parts being in uppermost position, a mandrel is suspended between the caps 46 as indicated by the broken lines of the drawing, the pivoted mounting of the bracket 52 facilitating the mandrel-mounting operation. The frame is then manually lowered until the mandrel is partly or wholly immersed in the bath and then raised again and the mandrel rotated to bring uppermost that portion of the mandrel which first made contact with the bath to expose the bubbles thereon caused by the entrapping of

air between the mandrel and the liquid of the bath.

The valve 59 is then actuated to permit air under pressure to issue from the nozzles 60 and by impinging against the mandrel, destroy said bubbles. The mandrel is then lowered into the bath and rotated continuously while a substantially undirectional electric current is supplied through the positive cable 65 and negative cable 66. The course taken by the current from the positive cable 65 is through the bars 15 to the journal bracket 21 and the pivoted bracket 52, thence to the respective bearing structures 24, 24, the horizontal shafts 41, 41, the blocks 47, 47, the contact fingers 48, 48, and to the mandrel 12. The electrical conductivity may be increased by lubricating the gears in the bearing structure 24 with a grease having a high graphite content. The current passing from the mandrel 12 through the liquid 11 to the receptacle 10 and thence to the negative cable 66, causes the deposition on the mandrel 12, in the form of a coherent coating 13, of negatively charged colloidal particles, such as the rubber particles in rubber latex, suspended in the liquid 11. When a deposit of sufficient thickness is obtained the current is interrupted, the mandrel is raised from the bath 30 and rotation is continued until all the liquid adhering thereto either drips back into the bath or is uniformly distributed upon the surface of the deposit on the mandrel. The mandrel may then be removed and the operation repeated.

Although my invention is described with reference to the coating of articles or mandrels by electrodeposition it will be evident that it may be adapted for mechanical coating by the omission of the cables 65 and 66 and the contact fingers 48, 48.

It will be seen that I have provided driving apparatus for coating processes in which there are no frictionally sliding surfaces in contact with the coating-bath, and wherein other advantages set forth in the statement of objects are attained.

Various modifications are possible within the scope of the appended claims.

50 I claim:

1. In combination, a rotatable member, a support for said member disposed out of alignment with the axis of rotation of the member, and a flexible, liquid-tight sleeve surrounding the support and connected at one end with the rotatable member in such manner as to rotate therewith and to exclude liquids from contact with frictionally engaging parts of the mechanism.

60 2. In combination, a rotatable member, a support for said member disposed out of alignment with the axis of rotation of the member and including driving means for the member, and a flexible, liquid-tight sleeve surrounding the support and driving means

and connected at one end with the rotatable member in such manner as to rotate therewith and to exclude liquids from contact with frictionally engaging parts of the mechanism.

3. In combination, a rotatable member, a support for said member disposed at an angle to the axis of rotation of the member, driving means for the member enclosed within the support, and a flexible, liquid-tight sleeve surrounding the support and connected at one end with the rotatable member in such manner as to rotate therewith and to exclude liquids from contact with frictionally engaging parts of the mechanism. 70

4. In combination, a rotatable member, a support for said member disposed at an angle to the axis of rotation of the member, a flexible, liquid-tight sleeve surrounding the support and connected at one end with the rotatable member in such manner as to rotate therewith and to exclude liquids from contact with frictionally engaging parts of the mechanism, and means for alternately immersing the rotatable member in a liquid bath and removing it therefrom. 80

5. In combination, a rotatable member, a support for said member disposed out of alignment with the axis of rotation of the member, and a flexible, liquid-tight, circumferentially corrugated sleeve surrounding the support and connected at one end with the rotatable member in such manner as to rotate therewith and to exclude liquids from contact with frictionally engaging parts of the mechanism. 95

6. In combination, a rotatable member, a support for said member disposed out of alignment with the axis of rotation of the member, and a helically corrugated, flexible, liquid-tight sleeve surrounding the support and connected at one end with the rotatable member in such manner as to rotate therewith and to exclude liquids from contact with frictionally engaging parts of the mechanism. 105

7. In combination, a rotatable member, a support for said member disposed out of alignment with the axis of rotation of the member, and an internally reenforced, circumferentially corrugated sleeve of resilient material surrounding the support and connected at one end with the rotatable member in such manner as to rotate therewith and to exclude liquids from contact with frictionally engaging parts of the mechanism. 110

8. In combination, a rotatable member, a support for said member disposed out of alignment with the axis of rotation of the member, and an internally reenforced, helically corrugated rubber sleeve surrounding the support and connected at one end with the rotatable member in such manner as to rotate therewith and to exclude liquids from contact with frictionally engaging parts of the mechanism. 120

9. In combination, a rotatable member, a support for said member disposed at an angle to the axis of rotation of the member, driving means for the member enclosed within the support, and a circumferentially corrugated rubber sleeve surrounding the support and connected at one end with the rotatable member in such manner as to rotate therewith and to exclude liquids from contact with frictionally engaging parts of the mechanism.
10. In combination, a rotatable member, a support for said member disposed out of alignment with the axis of rotation of the member and adapted to sustain the rotatable member beneath the surface of a liquid, driving means for the member enclosed within the support, and a circumferentially corrugated rubber sleeve surrounding the support and connected at one end in liquid-tight relationship with the rotatable member so as to rotate therewith, the other end of the sleeve extending at all times above the surface of the liquid.
11. In combination, a member rotatable about a horizontal axis, a curved support therefor, one end of the support being substantially co-axial with the rotatable member and the other end being substantially vertical, driving means for the rotatable member enclosed within the support, means adapted to lower and raise the rotatable member into and out of a liquid bath, and a circumferentially corrugated sleeve of resilient material surrounding the support, one end of the sleeve being connected with the rotatable member in liquid-tight relationship so as to rotate therewith and the other end extending at all times above the surface of the liquid.
12. In combination, a vertically movable frame, a pair of supports depending therefrom, the lower ends of the supports being curved toward one another, a pair of members rotatable about a common axis, the said members being located on the ends of the two supports and being adapted to grasp and sustain an object which is to be immersed and rotated in a liquid bath, driving means for the rotatable members contained within at least one of the supports, and circumferentially corrugated sleeves of resilient material surrounding the supports, one end of each sleeve being connected with the corresponding rotatable member in liquid-tight relationship so as to rotate therewith and the other end extending at all times above the surface of the liquid.
55. In witness whereof I have hereunto set my hand this 7th day of October, 1927.

GEORGE F. WILSON.
